E. G. SIEGFRIED INVENTOR

BY *Emil F. Lange*
ATTORNEY

UNITED STATES PATENT OFFICE.

EUGENE G. SIEGFRIED, OF LINCOLN, NEBRASKA, ASSIGNEE OF ONE-HALF TO AUGUST W. VOGT, OF LINCOLN, NEBRASKA.

MANIFOLD HEATER.

Application filed August 6, 1924, Serial No. 730,441.

To all whom it may concern:

Be it known that I, EUGENE G. SIEGFRIED, a citizen of the United States, residing at Lincoln, in the county of Lancaster and 5 State of Nebraska, have invented certain new and useful Improvements in Manifold Heaters, of which the following is a specification.

My invention is designed for use on internal combustion motors and it relates to that 10 general class of devices which are adapted to facilitate the ignition of the gasoline vapor when starting the engine. The purpose of my invention is the provision of a 15 manifold heater which may be connected in such a way that it will respond instantly and automatically with the starter to heat the explosive mixture before it reaches the cylinder. It is also my object to provide 20 such a manifold heater which is neat and attractive in appearance, which can be made at a low cost and which can be installed on the engine without the use of special tools. Having in view these objects and others 25 which will be pointed out in the description I will now refer to the drawings.

Figure 1 is a median longitudinal section of my manifold heater, the core and resistance coil being shown in full.

30 Figure 2 is a view and perspective of a portion of an internal combustion engine with my manifold heater attached thereto.

The heating cup 10 is lined on its sides and bottom with insulating material 11. 35 The open end of the cylinder cup 10 is internally screw threaded for the reception of a shouldered plug 13. The cylinder 10 is externally screw threaded at 12. The plug 13 is provided with a central conical 40 aperture for receiving the smaller end of the conical core 14. This core 14 is surrounded throughout its entire length by the insulation 15. Integral with the core 14 and projecting from its smaller end and beyond the plug is a binding post 16. Surrounding the binding post are two washers 45 17 and 18. The washer 17 is preferably made of rubber or other insulating material having more or less resistance, but the washer 18 is made out of copper or other soft metal having considerable conductivity. The binding post 16 is screw threaded for receiving the nuts 19 and 20. It will readily be seen that the pressure of the nut 50 19 will draw the core 14 into the conical

socket of the plug 13 and thus form a secure connection between the various parts. At the same time the core 14 is completely insulated from the plug 13 by means of the insulation 15 and 17. The nut 20 is relatively loose and merely serves to clamp the end of the wire.

Surrounding the core 14 is a resistance coil which is completely insulated from the walls of the cylinder 10 and from the body 60 of the core. One terminal of the resistance coil is connected with the core 14 at its free end while the other terminal of the resistance coil is connected with the plug 13 which constitutes the ground. The current 70 entering through the binding post 16 will traverse through and heat the coil 21.

In Figure 2 I have indicated the manner in which my manifold heater is applied to internal combustion engines. I first drill 75 an aperture in the manifold at the junction to receive the screw threaded portion 12 of my manifold heater. I then connect the manifold heater to the battery through the same switch which controls the starter. In Figure 2 my device as a whole is indicated by the letter A, the switch by B, the connection between the switch and the battery by C and the connection from the switch to the starter by D.

I find that my heater responds almost instantly when the current is turned on. The current must flow through the resistance coil since the coil is thoroughly insulated throughout its entire length. The heating 90 of the coil, however, is followed by the rapid heating of the cylinder 10, since the heating is confined in a narrow space surrounding the coil. It has been found by actual practice that the cylinder 10 can be heated red 95 hot within a few seconds after the current is turned on. The manner in which the heater is connected through the starting circuit also has decided advantages, since the heat will thus be applied only when the 100 motor is being started.

I am aware that gaskets and similar heating contrivances have been employed in the connections between the carburetter and the manifold for the purpose of warming the 105 gas as it leaves the carburetter. While such devices prove serviceable during the months of cold weather, I have found that they are located too near the manifold and too remote from the cylinders to give the best re- 110

sults. Such devices also do not give the intense heat that can be obtained from the use of my manifold heater.

My manifold heater is however adapted 5 for other uses than the one specifically described. As an oil heater for thinning and warming the oil when starting the engine in cold weather, my device has proved to be 10 remarkably successful under rigid tests. For this purpose the heater is made in a somewhat larger size but it is inserted 15 through the wall of the crank case in the same manner as with the manifold.

Having thus described my invention in 15 terms which will be readily understood by others skilled in the art to which it pertains, what I believe to be new and desire to secure by Letters Patent of the United States is:—

1. A manifold heater comprising a plug, 20 said plug being provided with a central conical aperture extending therethrough, a conical shaped conducting core seated within the aperture of said plug, said core being surrounded by an insulating sheath, a binding post integral with said core, an insulated 25 washer surrounding said binding post and bearing against said washer to secure the

core tightly in the aperture of the plug, and a resistance coil surrounding said insulated sheath, one of the terminals of said resistance coil communicating through said plug with the binding post and the other of the terminals having its ground connection in said plug. 30

2. A manifold heater comprising a cylinder which is closed at one end, a plug for closing the other end of said cylinder, said plug being provided with a central conical aperture, a conducting core which is so shaped as to fit snugly into the aperture of 35 said plug, said core being surrounded by a sheath of insulating material, a binding post integral with said core and projecting from said plug, a resilient insulated washer surrounding said binding post and bearing 40 against said plug, said binding post bearing against said washer for firmly drawing said core into aperture of said plug, and a resistance coil surrounding said insulating sheath, said resistance coil being grounded 45 in said plug and having its other terminal in the inner extremity of said core. 50

In testimony whereof I affix my signature.
EUGENE G. SIEGFRIED.
